[57] ABSTRACT

A light-intensifying device comprises a panel of integrated layers composed of a transparent base, a first transparent electrode layer, a photoconductive layer, a negative resistance layer, an electroluminescent layer, and a second transparent electrode. The device can prevent the halation appearing around the bright field of an output image.

1
LIGHT-INTENSIFYING DEVICE

This invention relates to a light-intensifying device, and particularly to a novel and improved light-intensifying device which can prevent halation appearing around the bright field of an output image when increasing the contrast of the image in a dark field.

A conventional light-intensifying device has layers, an electroluminescent layer and a photoconductive layer, which are sandwiched between two transparent electrodes, and the transparent electrodes are usually made from thin layers of tin oxide deposited on transparent glass plates. Usually, the electroluminescent layer is composed of zinc sulfide or zinc selenide as the active material, and the photoconductive layer is composed of cadmium sulfide or cadmium selenide as the active material. The input light is projected on the transparent electrodes adjacent to the photoconductive layer, and then an output light is observed at the other transparent electrode adjacent to the electroluminescent layer. Such a conventional device operates on the following principle: When a voltage is applied across the two transparent electrodes and input light is projected on the photoconductive layer, the voltage across the photoconductive layer decreases in accordance with the decrease of the resistivity of the photoconductive layer upon projection of input light thereon. Accordingly, the voltage across the electroluminescent layer increases, and so the input light is intensified. When the input light is composed of a light image, an intensified light image corresponding to the input light image can be observed.

Such a conventional light-intensifying device has a drawback that it is rather difficult to enhance the contrast of the dark field in the output light image. For example, an increase of the intensity of the input light causes halation, i.e., a halo, around the bright field in the output image.

Therefore, a fundamental object of this invention is to provide a novel and improved light-intensifying device which can prevent the halation appearing around the bright field in the output light image.

A further object of this invention is to provide a light-intensifying device including a negative resistance layer in addition to an electroluminescent layer and a photoconductive layer.

These objects are achieved by providing a light-intensifying device which comprises a panel of integrated layers consisting essentially of a transparent base; a first transparent electrode layer; an electricity-to-light conversion layer having a specific electric resistance, R ; a negative resistance layer having a voltage-current curve which has a transition point from a low resistance branch having a specific resistance R_l to a high branch having a specific resistance R_h during an increase of the voltage the transition point being at a critical voltage V_c ; a light-to-electricity conversion layer having specific electric resistances R_1 and R_2 when irradiated with light having intensities L_1 and L_2 , respectively, where L_1 is lower than and L_2 is higher than a critical intensity L_c , which causes said negative resistance layer to receive a voltage equal to said critical voltage V_c when said light-intensifying device is provided with a given voltage V ; and a second transparent electrode layer, said first transparent electrode layer, said electricity-to-light conversion layer, said negative resistance layer, said light-to-electricity con-

2

version layer, and said second transparent electrode layer being stacked in the recited order, whereby upon irradiation of a light image on said device to which a voltage V is applied, a unit area of said electricity-to-light conversion layer is energized by a voltage $RV/(R_1+R+R_l)$ or $RV/(R_2+R+R_h)$ when the corresponding unit area of said light-to-electricity conversion layer is irradiated with light of intensity L_1 or L_2 , and accordingly the halation around the bright field of the light image is eliminated.

These and other objects of this invention will be apparent upon consideration of the following detailed description taken together with the accompanying drawings wherein:

15 FIG. 1 is a schematic view of the fundamental construction of a light-intensifying device according to this invention;

20 FIG. 2 is a graph of the voltage versus current characteristic of a negative resistance layer of the device shown in FIG. 1;

25 FIG. 3 is a graph of the voltage versus current characteristics of a thermistor having a positive temperature coefficient of resistance for explaining the operation of the device of the invention; and

30 FIG. 4 is a schematic view of the construction of a light-intensifying device of this invention having a heating element embedded in a negative resistance layer.

Referring to FIG. 1, a light-intensifying device according to the invention comprises a panel of integrated layers as shown in FIG. 1. A first transparent electrode layer 2 is deposited on a transparent base 1 such as a glass plate. An electricity-to-light conversion layer 3 is formed on said first transparent electrode layer 2. A negative resistance layer 4 is formed on said electricity-to-light conversion layer 3. A light-to-electricity conversion layer 5 is formed on said negative resistance layer 4. A second transparent electrode layer 6 is deposited on said light-to-electricity conversion layer 5.

40 FIG. 2 shows the voltage versus current characteristic of said negative resistance layer 4. Said negative resistance layer 4 has a transition point 7 on the voltage-current characteristic curve at a critical voltage V_c . At that transition point 7, the resistance changes from a low resistance branch 8 having a specific resistance R_l to a high resistance branch 9 having a specific resistance R_h with an increase in the voltage, as shown in FIG. 2. The value of R_h is higher at least by 100 times than the value of R_l . Said light-to-electricity conversion layer 5 has specific resistances R_1 and R_2 for irradiation of light of intensities, L_1 and L_2 , respectively, where L_1 is lower than and L_2 is higher than a critical intensity L_c which causes said negative resistance layer 4 to receive a voltage equal to said critical voltage V_c . The value of R_1 is higher than the value of R_2 .

45 When a certain voltage V is applied to said light-intensifying device and a unit area of said light-to-electricity conversion layer 5 is irradiated with light having an intensity L_1 or L_2 , the voltage appearing at the corresponding unit area of said electricity-to-light conversion layer 3 is expressed as $RV/(R_1+R+R_l)$ or $RV/(R_2+R+R_h)$, respectively, where R is the specific resistance of said electricity-to-light conversion layer 3.

50 55 60 65 60 The brightness B of the light emitted from said electricity-to-light conversion layer 3 is related to the voltage V_E appearing at the layer 3 and it is expressed as follows:

$$B = KV_{En}$$

where n is, in practice, a value between 3 and 7, and K is a constant. Therefore, the brightness of the light emitted from a unit area of said electricity-to-light conversion layer 3 decreases in accordance with an increase of the light intensity from L_1 to L_2 of light irradiated on the corresponding unit area of said light-to-electricity conversion layer 5. Consequently, a clear light image in a dark field can be obtained without appearance of halation around the very bright field of the light image.

Said first transparent electrode layer 2 and said second transparent electrode layer 6 can be made of transparent thin films of tin oxide. Said electricity-to-light conversion layer 3 consists essentially of an electroluminescent material such as zinc sulfide or zinc selenide. Said light-to-electricity conversion layer 5 consists essentially of a photoconductive material such as cadmium sulfide or cadmium selenide. Said negative resistance layer 4 having a voltage-current characteristic curve as shown in FIG. 2 consists essentially of a thermistor element having a positive temperature coefficient of resistance (designated as a PTC thermistor in the following description). Said PTC thermistor layer is fabricated by applying a paste having powdered PTC thermistor dispersed in a vehicle to said electricity-to-light conversion layer 3 and curing said paste.

It is desirable to be able to change the critical voltage V_c easily so as to prevent halation from appearing around the bright field at various brightness. As shown in FIG. 3, the voltage-current curve of said PTC thermistor shifts from a curve 10 to a curve 12 through a curve 11 in accordance with an increase of the temperature of said PTC thermistor, and consequently the critical voltage shifts also from V_1 to V_3 through V_2 . Thus the critical voltage V_c can be shifted as desired by appropriately heating the device.

Referring to FIG. 4, in a panel comprising integrated layers consisting of a transparent base 16, a first transparent electrode layer 17, an electricity-to-light conversion layer 18, a negative resistance layer 19, a light-to-electricity conversion layer 20 and a second transparent electrode layer 21, which are stacked in the recited order, a heating element 22 is embedded in said negative resistance layer 18. Said heating element 22 consists of a metallic wire or a metallic thin film. Said negative resistance layer 19 consists essentially of a PTC thermistor element. The temperature of said negative resistance layer 19 varies with the electric current flowing through said heating element 22, and accordingly the critical voltage, V_c can be controlled by adjusting the heating current.

While there have been described at present what are believed to be the preferred embodiments of this invention, it will be obvious that various changes and modifications can be made therein without departing from the spirit or scope of the invention.

What is claimed is:

1. A light-intensifying device comprising a panel of integrated layers consisting essentially of a transparent base; a first transparent electrode layer; an electricity-to-light conversion layer having a specific electric resistance R ; a negative resistance layer having a voltage-current curve which has a transition point from a low resistance branch having a specific resistance R_l to a high resistance branch having a specific resistance R_h with an increase of the voltage, the transition point being at a critical voltage V_c ; a light-to-electricity conversion layer having specific electric resistances R_1 and R_2 in respect to irradiation of light having intensities L_1 and L_2 , respectively, where L_1 is lower than L_2 is higher than a critical intensity L_c which causes said negative resistance layer to receive a voltage equal to said critical voltage V_c when said light-intensifying device has a given voltage V applied thereto; and a second transparent electrode layer, said first transparent electrode layer, said electricity-to-light conversion layer, said negative resistance layer, said light-to-electricity conversion layer, and said second transparent electrode layer being stacked in the recited order, whereby upon irradiation of a light image on said device having said given voltage V applied thereto, a unit area of said electricity-to-light conversion layer is energized by a voltage $RV/(R_1+R+R_l)$ or $RV/(R_2+R+R_h)$ when the corresponding unit area of said light-to-electricity conversion layer is irradiated with light having a light intensity L_1 or L_2 , and accordingly halation around the bright field of the light image is eliminated.

2. A light-intensifying device as claimed in claim 1, wherein said electricity-to-light conversion layer consists essentially of an electroluminescent material.

3. A light-intensifying device as claimed in claim 1, wherein said negative resistance layer consists essentially of a thermistor layer comprised of a finely divided powder having a positive temperature coefficient of resistance.

4. A light-intensifying device as claimed in claim 1, wherein said light-to-electricity conversion layer consists essentially of a photoconductive material.

5. A light-intensifying device as claimed in claim 1, wherein said negative resistance layer has a heating element embedded therein for controlling the size of said critical voltage, V_c .
